PAGE 2

Fig. 3

Fig. 4

Fig. 5

Fig. 6

FIGURE 1 is a top perspective view of a storage tank showing my new design;

FIGURE 2 is a bottom perspective view thereof;

FIGURE 3 is a top perspective view of a modified form thereof;

FIGURE 4 is a bottom perspective view of the modified form shown in FIGURE 3;

FIGURE 5 is an enlarged cross-sectional view thereof taken on line 5—5 of FIGURE 1; and

FIGURE 6 is an enlarged cross-sectional view thereof taken on line 6—6 of FIGURE 1.

The undisclosed sides of each modification are the same as the respective sides shown.

I claim:

The ornamental design for a storage tank, as shown and described.
